DESIGN FOR A TOASTER OR LIKE ARTICLE

Sven Ohrvel Carlson, West Orange, N. J., assignor to Thomas A. Edison, Incorporated, West
Orange, N. J., a corporation of New Jersey

Application March 7, 1934, Serial No. 50,969

Term of patent 7 years

To all whom it may concern:

Be it known that I, SVEN OHRVEL CARLSON, a citizen of the United States, residing at the town of West Orange, in the county of Essex and State of New Jersey, have invented a new, original, ornamental Design for a Toaster or Like Article, of which the following is a specification, reference being had to the accompanying drawing, forming a part of this specification,

The figure is a perspective view of a toaster showing my new design.

I claim:

The ornamental design for a toaster or like article, substantially as shown.

SVEN OHRVEL CARLSON.
